UNITED STATES PATENT OFFICE.

JOHN A. ROBERTSON, OF ROCHESTER, NEW YORK, ASSIGNEE TO EASTMAN KODAK COMPANY, OF ROCHESTER, NEW YORK, A CORPORATION OF NEW YORK.

LATCH FOR CAMERAS.

Application filed August 16, 1922. Serial No. 582,120.

To all whom it may concern:

Be it known that I, JOHN A. ROBERTSON, a citizen of the United States, residing at Rochester, in the county of Monroe, State 5 of New York, have invented certain new and useful Improvements in Latches for Cameras, of which the following is a specification.

My present invention relates to photography and more particularly to photographic cameras of the type embodying a body portion and a removable or displaceable back portion cooperating therewith and the invention has for its object to provide a 10 simple, efficient and inconspicuous latch for securely locking the parts together in a manner making it convenient for the operator to engage or release the same. The improvements are directed in part toward fitting a 15 sliding latch with a frictional tensioning means of a simple character readily manufactured and assembled and which maintains the latch in any of its adjusted positions. To these and other ends the invention 20 consists in certain improvements and combination of parts all as will be herein-after more fully described, the novel features being pointed out in the claim at the 25 end of the specification.

In the drawings:

Figure 1 is a side view of a camera provided with a latch constructed in accordance with and illustrating one embodiment of my invention, the carrying handle being removed in this and the other views.

Figure 2 is a similar enlarged view partly broken away and partly in vertical section transversely through the latch.

Figure 3 is a top view of the camera showing the latch engaged.

Figure 4 is a similar view showing the latch disengaged.

Figure 5 is a longitudinal central section through the latch on the line 5—5 of Figure 3.

Figure 6 is a perspective view of the tensioning washer plate.

Similar reference numerals throughout the several views indicate the same parts. In the present embodiment I have illustrated my invention as applied to a folding pocket hand camera of a familiar type comprising the body portion 1 and a back 2 removable therefrom and cooperating therewith on the line 3 in connection with the

usual light sealing devices indicated generally at 3^a and 3^b in Figure 2. At the bottom the light sealing flanges are formed with interlocking shoulders 4 so that when the bottom of the back is first engaged with the bottom of the body and the back then swung into complete contact with the body the disengagement of the bottom portion must follow the disengagement of the top portions so that locking devices arranged at the top are controlling.

In the practice of my invention I provide a latch at the top of the camera comprising in the present instance a sliding bolt 5 on the body and a pair of upstanding catch pins 6 spaced apart along the top edge of the back 2. The bolt 5 is provided with two bayonet slots 7 forming engaging fingers 8 having cam edges so that when they cooperate with the pin 6 they will draw the back in 75 against the body. Two longitudinal slots 9 in the bolt travel on two headed guide pins 10 on the body 1 and the bolt is confined beneath the heads of these pins. Projecting from the same side of the bolt as the engaging fingers 8 but also projecting beyond the latter is a suitable finger piece extension 11 by means of which the bolt is operated and which becomes readily accessible to the fingers at one side of the usual carrying 80 strap (not shown) that spans the top of cameras of this kind.

In order to maintain the bolt yieldably in either its engaged or disengaged position, I provide tensioning device 12 shown in detail in Figure 6. This comprises in the present instance a washer plate or strip secured beneath shoulder 13 on the guide pins 10 which latter are riveted to the shell of the camera body as clearly shown in Figure 85 5. The apertures 14 in the washer plate through which the pins or rivets pass are spaced apart a very slightly greater distance than are these pins so that when the plate is applied to the pins it buckles or bows in 100 an upward direction as shown in Figure 5. The parts all being held together by the rivets, the result of this is that bulging plate exerts a substantial pressure against the bolt 5 and offers a frictional resistance 105 sufficient to maintain it with desired security in any adjusted position though allowing the bolt an easy sliding movement when sufficient energy is exerted on the finger piece 11.

A latch of this character is readily of stamped parts and easily assembled by relatively unskilled workmen as it is self-adjusting.

6 I claim as my invention:

The combination with a camera body and a back cooperating therewith, of a latch for releasably securing said parts together comprising a catch on one part, spaced guide pins on the other, a sliding bolt movable on

the guide pins and adapted to engage the catch, and a washer plate beneath the bolt consisting of a plate having spaced apertures through which the guide pins pass, said apertures being spaced apart a distance 15 slightly greater than that between the guide pins to cause the plate to bow and exert a frictional tension on the bolt.

JOHN A. ROBERTSON.
